UNITED STATES PATENT OFFICE.

GEORGE F. WERTH, OF CHICAGO HEIGHTS, ILLINOIS, ASSIGNOR TO CANEDY-OTTO MFG. CO., OF CHICAGO HEIGHTS, ILLINOIS, A CORPORATION OF ILLINOIS.

RADIAL DRILL.

1,278,407.

Specification of Letters Patent. Patented Sept. 10, 1918.

Application filed September 7, 1917. Serial No. 190,121.

To all whom it may concern:

Be it known that I, GEORGE F. WERTH, a citizen of the United States, residing at Chicago Heights, in the county of Cook and State of Illinois, have invented certain new and useful Improvements in Radial Drills, of which the following is a specification.

My invention relates to improvements in radial drills, and has particular reference to a type of radial drill which may be used interchangeably as an ordinary radial drill or as an ordinary drill press.

The principal objects of the invention are to provide a drill of the class described which shall be self-contained while at the same time of such design and construction that it may be applied to the wall or post of a building or other suitable vertically extending support; to provide a drill of the class described which shall have all the advantages of a wall type radial drill and an ordinary drill press in the same piece of apparatus; to provide a construction which shall be of simple design while having the rigidity required to withstand heavy drilling; to provide a construction which shall be economical to manufacture, while being convenient and simple to manipulate and efficient in operation; and, in general, to provide an improved radial drill of the character referred to.

In the drawings, which illustrate a preferred embodiment of my invention—

Figure 1 is a side elevation of the device; Fig. 2 is a section taken on the line 2—2 of Fig. 1;

Fig. 3 is a section taken on the line 3—3 of Fig. 1; and

Fig. 4 is a section taken on the line 4—4 of Fig. 1.

Referring to the drawings, 10 represents either the wall or a post of a building to which are secured, by means of suitable bolts 11, the upper and lower flanges 12 and 13, of a cast iron bracket 14. Said bracket 14 has upper and lower heavy outstanding lugs or seats 15 and 16, said seats 15 and 16 having bolted thereto caps 17 and 18. The parts 15 and 17, and 16 and 18, are bored out to constitute clamps for an axially vertical heavy turned cylindrical column 19, said column being rigidly secured in position by tightening up the bolts 20 and 21.

The clamp arms 15 and 16 of the bracket 14 are spaced apart a sufficient distance to

accommodate the hub 22 of an arm designated as a whole 23 journaled upon said column 19. The said hub 22 is preferably split, as shown at 24, and equipped with clamping screws 25 and 26 which pass through the split lugs 27 and 28 for the purpose of enabling the said arm 23 to be locked securely upon said column in any desired angular position.

Over the top of the fixed column 19 there is located a rigid mounting 28* in which is journaled an axially horizontal shaft 29, power-driven by a suitable pulley 30 and belt 31. To the inner end of said shaft 29 there is keyed a bevel gear 32 which drives an axially vertical bevel gear 33 journaled in the upper end of the column 19. Said bevel gear 33 is coaxial with the said column 19 and drives a bevel gear 34 keyed to the end of a horizontal shaft 35 journaled at its inner end in the upper part of a small arm or bracket 36 extending upwardly from the main horizontal arm 23.

Said shaft 35 is milled out longitudinally to provide a key-way 37 accommodating a key for driving the bevel gear 38 which actuates the spindle of the sliding drill-head 39. The drill-head 39, together with its associated mechanism for driving and feeding the spindle and for effecting radial sliding movement of the head, is of approved and well known construction, and requires no detailed description in this application.

The column 19 which, as shown, is of considerable diameter and hence designed for great rigidity, is extended a considerable distance down below the bracket arm 16 so as to accommodate the sliding hub 40 of a heavy arm 41 arranged to rotate upon said column 19. The said hub 40, as shown in Figs. 3 and 4, is equipped with a split clamp portion 42, similar to the clamping means of the radial arm 23. The outer end of the said arm 41 is formed with an axially vertical boss 43 for rotatably receiving the stem 44 of a circular drilling table 45. The table 45 can be locked against rotary movement in the boss 43 by means of a split clamp 46.

Since the table 45 and arm 41 are of considerable weight, when the device is made in large sizes, I prefer to utilize special means for raising and lowering said table 45 whenever it is necessary to adjust the

105

110

height of the table. To this end, I employ an axially vertical adjusting screw 47 rotatably mounted in a pair of bracket bearings 48 and 49 bolted, respectively, to the arm 16 and the lower extremity of the column 19. Said adjusting screw 47 is driven by means of a bevel gear 50 pinned to the upper end of the said screw 47 and operated by an inter-meshing bevel gear 51 rotatably mounted upon a fixed horizontal stem 52 constituting an integral part of the bracket 48. Keyed to the hub of the bevel gear 51 is a manually-actuated crank 53. The boss 54 of a small casting 55 is tapped vertically to fit the said adjusting screw 47, rotation of which by the means just described, raises and lowers the bracket 55 in an obvious manner. Vertical movement of the bracket 55 is transmitted to the hub 40 of the arm 41 by means of a pair of lugs 56 and 57 constituting integral parts of the said bracket 55 and spaced apart a sufficient distance to admit the hub 40. Preferably, the lower lug 57 is made wide enough to embrace a considerable arc of the column 19 (see Fig. 3) so as to eliminate any tendency of the bracket 55 to rotate with the screw 47.

In view of the above description, the operation of the device is self-evident. When it is desired to use the apparatus purely as a radial drill,—for instance, when operating upon some part of a motor truck, the clamp 42 is released, enabling the arm 41 and table 45 to be swung around out of the way, thereby permitting the object to be drilled to be rolled or otherwise moved under the radial arm 23. The apparatus thus has every advantage of a radial drill of the ordinary wall type.

The apparatus may also be efficiently employed for all purposes for which the usual drill press with a fixed spindle has heretofore been used. When so employed, the drill-head 39 is adjusted in such position

along the radial arm 23 as to bring the center of the spindle above the center of the drilling table 45. The radially adjustable feature of the device may of course also be utilized in connection with the work-supporting table 45, where objects of only moderate dimensions are to be operated upon.

The preceding detailed description should not be construed as any limitation of the invention, the scope of which should be determined by reference to the appended claims.

I claim—

1. The combination of a vertically extending support, a bracket secured to the side of said support, said bracket being provided with a pair of outstanding lugs, an axially vertical column mounted in said lugs and provided with a depending extension, an arm mounted between said lugs to swing in a horizontal plane around the axis of said column, a drilling head mounted to slide along said arm, means for driving said head, and a drilling table rotatably mounted upon the lower extension of said column. 65 70

2. The combination of a vertically extending support, a bracket rigidly secured to said support and provided with a pair of vertically spaced lugs having axially aligned circular seats formed therein, an axially vertical cylindrical column having its upper end mounted in said seats, an arm provided with a hub journaled on said column between said lugs, a drilling head horizontally slideable along said arm, means for driving said head, said column having a lower extension extended freely in space below said lugs, and a drilling table below said arm and rotatably mounted co-axial with and upon said lower extension, said column being of sufficient rigidity to withstand drilling pressure upon said table without extraneous support. 75 80 85

GEORGE F. WERTH.
